(57) **CLAIM**

The ornamental design for a containment system, as shown and described.

DESCRIPTION

FIG. 1 is a perspective view of a containment system in accordance with the present disclosure.

FIG. 2 is a front elevational view of the containment system of FIG. 1.

FIG. 3 is a top plan view of the containment system of FIG. 1.

FIG. 4 is a bottom plan view of the containment system of FIG. 1.

FIG. 5 is a rear elevational view of the containment system of FIG. 1.

FIG. 6 is a side elevational view of the containment system of FIG. 1; and,

FIG. 7 is an opposite elevational view of the containment system of FIG. 1.

The broken lines are for illustrative purposes only, and form no part of the claimed design.
